United States Patent Office

Des. 188,590
Patented Aug. 16, 1960

188,590

SHOE

Duke J. Rose, Nashville, Tenn., assignor to Genesco Inc., Nashville, Tenn., a corporation of Tennessee

Filed Apr. 20, 1959, Ser. No. 55,583

Term of patent 14 years

(Cl. D7—7)

FIG.1

I claim:

The ornamental design for a shoe, as shown.
